CLAIM

We claim the ornamental design for a portable/wearable electronic device, as shown and described.

DESCRIPTION

FIG. 1 is a perspective view of a portable/wearable electronic device, showing a first embodiment of our new design;

FIG. 2 is a left side view of the first embodiment;

FIG. 3 is a view of a first end of the first embodiment;

FIG. 4 is a top view of the first embodiment;

FIG. 5 is a view of a second end of the first embodiment;

FIG. 6 is a right side view of the first embodiment;

FIG. 7 is a bottom view of the first embodiment;

FIG. 8 is a perspective view of a portable/wearable electronic device, showing a second embodiment of our new design;

FIG. 9 is a left side view of the second embodiment;

FIG. 10 is a view of a first end of the second embodiment;

FIG. 11 is a top view of the second embodiment;

FIG. 12 is a view of a second end of the second embodiment;

FIG. 13 is a right side view of the second embodiment;

FIG. 14 is a bottom view of the second embodiment;

FIG. 15 is a perspective view of a portable/wearable electronic device, showing a third embodiment of our new design;

FIG. 16 is a left side view of the third embodiment;

FIG. 17 is a view of a first end of the third embodiment;

FIG. 18 is a top view of the third embodiment;

FIG. 19 is a view of a second end of the third embodiment;

FIG. 20 is a right side view of the third embodiment; and,

FIG. 21 is a bottom view of the third embodiment.

Dashed lines in the figures are for illustrative purposes only and form no part of the claimed design. In FIGS. 15-21 different colors of the portable/wearable electronic device are illustrated by different patterns of shading.
